Primary Examiner — Steven J Czyz*(74) Attorney, Agent, or Firm* — Ralph E. Smith**CLAIM**

The ornamental design for a hood latch, as shown and described.

DESCRIPTION

FIG. 1 is a left side front perspective view of a hood latch showing our new design;

FIG. 2 is a right side front perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view.

In the drawings, evenly-spaced broken lines depict portions of the hood latch that form no part of the claimed design; the dash-dot-dash lines represent the boundary of the claimed design and forms no part thereof.

1 Claim, 8 Drawing Sheets(56)
